UNITED STATES PATENT OFFICE.

CHARLES A. HAMMEL, OF LOS ANGELES, CALIFORNIA.

HYDROCARBON-BURNER.

No. 834,469.

Specification of Letters Patent.

Patented Oct. 30, 1906.

Application filed October 19, 1905. Serial No. 283,526.

To all whom it may concern:

Be it known that I, CHARLES A. HAMMEL, a citizen of the United States, residing at Los Angeles, in the county of Los Angeles and State of California, have invented new and useful Improvements in Hydrocarbon-Burners, of which the following is a specification.

The objects of my invention are to provide a hydrocarbon-burner composed of a number of parts easily assembled and disassembled, in which duplicate parts may be substituted for any of the parts injured or destroyed by continuous use or otherwise; to provide a burner that will practically atomize all the crude oil fed thereto, and thereby economize in the use of oil and at the same time produce the largest amount of heat therefrom.

A further object is to divide the steam into two jets, the one being directed at right angles against the other, both jets being regulated by one supply-valve and the oil being fed to the burner between the two jets of steam.

I accomplish these objects by means of the device described herein and shown in the accompanying drawings, in which—

Figure 1 is a perspective view of a hydro-carbon-burner embodying my invention, the oil and steam supply pipes being broken away. Fig. 2 is a vertical section of my burner, taken on line 2 2 of Fig. 5, looking in the direction indicated by the arrow-head thereon. Fig. 3 is a vertical longitudinal section taken of the burner on the line indicated by line 3 3 of Fig. 6 looking in the direction indicated by the arrow-heads thereon. Fig. 4 is a perspective view of the core or central part of the burner removed from the outer shell or casing. Fig. 5 is a transverse section of the device, taken on line 5 5 of Fig. 2, looking in the direction indicated by the arrow-heads thereon. Fig. 6 is a transverse section of the burner, taken on line 6 6 of Fig. 2, looking downwardly in the direction indicated by the arrow-heads marked thereon. Fig. 7 is a perspective view of a modified form of my burner adapted for use in a locomotive-engine. Fig. 8 is an elevation of the modified form with the face-plate removed. Fig. 9 is a vertical central section taken on line 9 9 of Fig. 8.

In the drawings, A represents the internal member or core, centrally disposed in the outer casing or shell B. This central core is provided with a screw-threaded aperture A', arranged to register with a screw-threaded

opening B' in the shell B for screw-threaded engagement with the oil-supply pipe C, through which oil is fed to the burner, the usual regulating-valves for regulating the 60 quantity of oil and steam fed to the burner not being shown. This opening A' forms an oil-receiving chamber and terminates in the mixing-chamber K, from which the vertical oil-supply channel D in turn communicates 65 at its lower end with the discharge-orifice E, through which the combined oil and steam is ejected into the combustion-chamber.

The bottom of the core is provided with the cavity A'', which forms a steam-receiving and distributing chamber disposed immediately above the screw-threaded opening B'' in the shell, into which the steam-supply pipe F is screwed. Extending from this distributing-chamber upwardly, one on each side thereof and on each side of the mixing-chamber, are the two upwardly-extending steam-supply ducts G, which communicate with the cavity H, which forms a steam-spreading chamber, in which the steam is spread out and passes downwardly through the narrow semicircular opening I, (see Fig. 5,) formed at this point between the core and the casing B, into the mixing-chamber and commingles with the oil therein, from which it passes downwardly on its way to the discharge-orifice E.

By providing a downwardly-extending steam-duct from the spreading-chamber above to the mixing-chamber below, which 90 will impinge at right angles upon the steam-jet issuing from the bottom spreading-chamber toward the discharge-orifice, thus one jet being directed against the other at right angles and the oil being fed between them 95 will completely mix the steam and oil and form a combustible gas before leaving the discharge-orifice of the burner.

In addition to this means of feeding steam to the burner I have provided a narrow supplemental steam-discharge orifice J, leading directly from the bottom of the steam-distributing chamber to the discharge-orifice. This orifice J being narrow and somewhat limited in capacity will supply only a part of the steam fed to the burner. The steam passing in a thin sheet through the orifice J will contact and unite with the mixed steam and oil passing downwardly through the channel D on its way to the discharge-orifice. The combined effect of the feeding steam through two orifices I and J, acting on the oil, will cre- 105 110 115

- ate (in addition to their combined effect in atomizing the oil) a suction and assist in drawing the oil from the oil-supply. The result is a double atomizer and an inside mixer. The oil will be converted into a vapor by the time the mixture reaches the final steam-jet at the outlet-orifice. This special arrangement enables me to dispense with the necessity of heating the oil fed to the burner, and the usual pressure put on the oil-supply may be dispensed with. By this arrangement the lower jet of steam serves as a protection to the bottom of the discharge-orifice from the wearing action of the foreign matter—such as boiler compound, sand, &c.—in the combined steam and oil as it comes downwardly from the mixing-chamber and prolongs thereby the lifetime as well as the efficiency of the burner.
- 20 The form of burner shown in Figs. 1 to 6, inclusive, is adapted to throw outwardly a fan-shaped blaze, while the form of burner shown in Figs. 7 to 8, inclusive, is adapted for use in a locomotive-boiler, wherein a longitudinal flame is required and is especially adapted for use in locomotive-boilers.
- Having described my invention, what I claim as new, and desire to secure by Letters Patent, is—
- 30 1. An oil-burner provided with an outer shell having a central cylindrical bore therein extending from the top thereof nearly to the bottom, said shell adapted to receive a cylindrical core, the said shell having a screw-threaded opening in the back thereof for the reception of an oil-supply pipe, and a screw-threaded opening in the bottom thereof for the reception of a steam-supply pipe, and a discharge-orifice extending outwardly from the bottom thereof, in combination with a cylindrical core having a recess in the bottom thereof to form a distributing-chamber; a recess close to the top thereof to form a spreading-chamber; ducts leading from the distributing-chamber to the spreading-chamber, the said core being provided with a central opening or recess to form a mixing-chamber, a portion of the said core being cut away below the spreading-chamber and extending to the mixing-chamber to leave an opening between that portion of the core and the outer shell when the core is in place in the shell for the passage downwardly of the steam from the spreading-chamber to the mixing-chamber, the said core having a larger cut extending from the mixing-chamber to the discharge-opening to form a passage-way for the passage downwardly of the combined oil and steam from the mixing-chamber to the discharge-orifice.
- 60 2. An oil-burner having a discharge-orifice; an oil-receiving chamber; a spreading-

chamber; a steam-receiving chamber; ducts leading from the steam-receiving chamber to the spreading-chamber and an opening for 65 the passage of steam from the steam-spreading chamber to a mixing-chamber; a mixing-chamber communicating at one end with an oil-supply pipe and having at the other end thereof a downwardly - extended opening 70 communicating with the discharge-orifice.

3. An oil-burner provided with a casing, a cylindrical core having recesses formed therein for a receiving-chamber, a mixing-chamber and a spreading-chamber; the receiving-chamber communicating directly with the steam-supply and having ducts extending therefrom and communicating with the spreading-chamber; an orifice extending outwardly and communicating with the discharge-orifice, an orifice extending downwardly from the spreading-chamber into the mixing-chamber and a larger orifice extending 80 downwardly from the mixing-chamber to the discharge-orifice, the said mixing-chamber being in communication with the oil-supply.

4. An oil-burner comprising a cylindrical shell and a cylindrical core adapted to fit thereinto, the shell having a cylindrical bore 90 therein extending from the top to near the bottom thereof, on the side thereof a screw-threaded opening for the reception of an oil-pipe, on the bottom thereof a screw-threaded opening for a steam-pipe, and a slit in the 95 face thereof to form a discharge-orifice; the cylindrical core adapted to fit into the bore of said shell and having in the bottom thereof a recess to form a receiving-chamber; ducts extending from the top of said chamber to a 100 slit in the upper portion of the core to form a spreading-chamber; and having also a cut-away portion on the bottom thereof to form an opening communicating with the discharge-orifice, the said receiving-chamber 105 communicating when in place in the shell with a steam-supply pipe; and a cut-away portion of said core extending from the spreading-chamber downwardly to a mixing-chamber; the mixing-chamber centrally disposed in said core and communicating with the oil-supply; and an enlarged cut-away portion extending from the mixing-chamber 110 to the bottom of the core to leave a passage-way for the passage of combined steam and oil from the mixing-chamber to the discharge-orifice.

In witness that I claim the foregoing I have hereunto subscribed my name this 12th day of October, 1905.

CHARLES A. HAMMEL.
